UNITED STATES PATENT OFFICE.

ALVAH L. POWELL, OF ROUNDUP, MONTANA, ASSIGNOR TO THE A. L. POWELL POWER COMPANY INCORPORATED, A CORPORATION OF MONTANA.

ENGINE.

Application filed December 10, 1919. Serial No. 343,952.

To all whom it may concern:

Be it known that I, ALVAH L. POWELL, a citizen of the United States, residing at Roundup, county of Musselshell, State of 5 Montana, have invented a certain new and useful Improvement in Engines, of which the following is a full, clear, and exact description, such as will enable others skilled in the art to which it appertains to make 10 and use the same, reference being had to the accompanying drawings, forming part of this specification.

This invention relates to certain new and useful improvements in internal combustion engines and in the present case is shown embodied in a two cycle type of engine but should not be limited thereto as the same principle may be incorporated and used in connection with an engine of more than the 20 two cycle type.

The principal object in the present invention resides in the novel manner of building up and storing for future use a pre-compressed charge of air.

Another object of the present invention 25 is the manner in which this precompressed charge is formed during the ordinary cycle of action of the engine.

Still another object of the invention deals 30 with the peculiar manner of transferring the power derived from the explosion or working cylinder to the crank shaft. This latter feature I am enabled to accomplish in the case by utilizing the type of inter- 35 gearing between the piston rod and the crank shaft disclosed in my copending application Serial No. 343,951 whereby the said elements are driven at a different ratio of speed.

With these and other objects in view it 40 will be apparent to those skilled in the art that certain variations and changes may be resorted to without sacrificing any of the spirit of the invention and the scope of protection contemplated will appear from the claim.

In the attached drawings I have merely 50 illustrated the preferred embodiments of the invention wherein Fig. 1 is an end elevation, partly in section showing the piston in its firing position. Fig. 2 is a cross section through the center portion of the engine illustrating the type of valve used in Fig. 1. Fig. 3 is an end elevation partly in section, illustrating a modified form of the

engine. Fig. 4 is a cross section through the head of the engine illustrating the type of valve used in Fig. 3. Fig. 5 is a detailed view of the inlet cam used in connection with the rotatory type of valve shown in Fig. 1. Fig. 6 is a detailed view illustrating the exhaust cam used in connection with Fig. 1. Fig. 7 is an end elevation partly in section of a further modification somewhat along the lines suggested in Fig. 3 but in this instance using a sliding valve. Fig. 8 is a perspective view of the type of valve in Fig. 7. Fig. 9 is a fragmentary sectional view of the upper portion of the engine showing the parts in the position that they will assume at the end of the firing stroke. Fig. 10 is a view similar to Fig. 9 but showing the parts at the beginning of the exhaust stroke. Fig. 11 is a fragmentary cross section taken on (11-11) Fig. 10. Fig. 12 is a modified form of slot which may be used in place of the disclosure made in Fig. 1 and Fig. 13 is a modification.

Referring more in detail to the drawings wherein similar letters of reference indicate like parts throughout the several views, (1) indicates an engine base or case into which is housed or enclosed the operating mechanisms such as crank shafts, cam shafts, etc. Arranged in position on the base (1) is a waterjacketed cylinder (2) which may be cast integral or bolted in any suitable manner to the top of the base. This cylinder, in the present case, has also formed therewith auxiliary cylinders (3-3) arranged on the sides thereof. Over the cylinder (2) and the compression cylinders (3) is arranged a cover or housing (4), the peripheral edges of which are securely fastened in any suitable manner to the edges of the cylinder casting. Between this cover (4) and the top of the cylinder casting is provided a chamber (5), the inlet to which is through the passages (6-6) through the upper end of the auxiliary cylinders (3). These passages (6-6) are closed by normally spring-pressed valves (7-7), the tension of which may be adjusted by (8-8), screw-threadedly secured on to the valve rods above the springs (9-9). The outlet from storage chamber (5) is through the passage (10) leading into the compression chamber of the engine. This passage (10), as shown in Figs. (1) and (2) is controlled by a rotatory type of valve (11),

which valve is termed the inlet valve, and is actuated by cam (12) located on the crank shaft of the engine. The connection between the crank shaft and the valve (11) is through suitable link mechanism illustrated at (13). The head of the cylinder (2) is also provided with an exhaust passage (14) which is controlled by the rotatory valve (15) operated through suitable links 10 from the cam (16) arranged on the crank shaft.

Arranged within the cylinder (2) there is a reciprocating piston (16) and rigidly secured thereto is a piston rod (17), the lower end of which is provided with a cross head indicated at (18). Connected to the crank shaft through a slotted aperture indicated at (18') is a reciprocating member (19), between which member and the cross head (18) is interposed a peculiar type of gearing which is specifically covered in my copending application Serial No. 343,951. It might be well to state at this point that the throw of the crank shaft is through a shorter range than the full movement of the piston head and it is through these different ratios of movement that I am enabled to increase the efficiency of the power stroke that will be ultimately delivered to the crank shaft. This variance of movement is accomplished by the type of intergearing shown between the piston rod and the member connected to the crank shaft.

Arranged within the auxiliary cylinders (3) are compression pistons (20-20), the actuations of which are always in opposition to the movement of the working piston. These compression pistons will, in their descent, draw through side passages (21-21) a charge of gas from carburetors or any other conventional type of vaporizing element. These passages are controlled by check or other suitable valves indicated at (22). In order to accomplish this opposing movement between the piston (16) and the compression pistons (20-20) I provided the latter with ratchet stems (23-23) which are adapted to mesh with gears (24-24).

The type of engine illustrated in Fig. 3 is slightly modified from that shown in Fig. 1 in that the connection between the piston head and the crank shaft is by a direct connecting rod (25), which, at its lower end is provided with an elongated slot (26) through which the crank shaft is adapted to actuate. In this showing the piston rod (25) is side-racked so as to gear with adjacent segmental gears (27-27) which are journaled in any suitable manner within the base (1). The ratio of movement between the piston (16) and the compression pistons (20-20) is substantially the same as that shown in Fig. 1. For the purpose of illustration we will say that they are geared 6 to 4, that is, the piston moves through a 6"

stroke whereas the compression pistons move only 4". Also in this type, shown in Fig. 3, in place of the rotatory valves shown in Fig. 1 is used a reciprocating type of valve and in order to prevent the precompressed charges within the storage chamber from opening the valve (28), I provide a second valve (29), which second valve is arranged in opposition to that of (28). In order to operate this type of valve I provide a double operating valve mechanism shown in Fig. 3 by which the pivotally-mounted arms (30-30) are actuated in opposite directions by elliptical member (31), which in turn is operated through suitable links from the crank shaft of the engine upon which is arranged an operating cam. As shown in Fig. 4 there is also provided an exhaust valve (32) which is likewise cam operated from the crank shaft of the engine. The type as shown in Fig. 3 is one in which the throw of the crank shaft equals the movement of the piston rod.

In the modifications shown in Figs. 7, 8, 9, 10 and 11 the parts are substantially as shown in Fig. 3, with the exception of the specific type of valve employed. In the present instance I employ a transversely sliding valve (33) which is provided with suitable apertures so as to initially admit the charge to the compression cylinders, further admitting them into the combustion chamber and ultimately allowing the passage of the exhaust. These passages are brought into proper registration with the various inlet and outlet passages by a rotatable cam (34). This cam is actuated from the crank shaft by any suitable mechanism, but as shown in the present case, for illustration, by chain (35) arranged around sprockets (36) and (37) on the crank shaft and cam shafts respectively. Interposed between the cam and one end of the slide valve (33) is a rocking link mechanism generally indicated as at (38). The opposite end of the slide valve (33) is tensioned by an expandable spring (39) resting at one end against the valve and at its opposite end against a bracket (40).

A complete operation of the device is as follows:—Assuming the parts to be in a position as shown in Fig. 1, the compressed charge that has been delivered to the head of the cylinder (2) is exploded thereby forcing the piston (16) downward and during said movement the compression cylinders (20) will force the charge of gas that they have drawn in, up into the storage chamber (5). This precompressed charge is held within the chamber (5) until the piston (16) again arrives at its upper limit. During this up-stroke of piston (16), it will, of course, be understood that the compression pistons are moved downwardly thereby drawing in a fresh charge from the carburetor (41).

retor through the passages (22). While the piston (16) is at its highest point the inlet valve is momentarily opened thereby allowing a portion of the precompressed charge 5 from the storage chamber (5) to enter the combustion chamber. During the up-stroke of the piston, the exhaust valve is held in its open position throughout the entire up-stroke and is closed just before the inlet valve is 10 opened. The weight 17' shown in Fig. 13 may be fastened to the piston rod to increase the efficiency of the engine.

I claim—

15 In an engine of the class described comprising a power cylinder and working piston therein, a rod connected to said piston and

having a transversely slotted head, auxiliary cylinders, a compression piston arranged within each of said auxiliary cylinders, a rod connected to each of said compression pistons, each of said rods having a racked portion, a pinion in mesh with the racked portion and means acting within the slotted head of the working piston rod for driving the pinion and thereby the compression, pistons in opposite direction to that of the working piston and at a relatively different ratio of speed to that of said working piston.

20 In testimony whereof I hereunto affix my signature this 10th day of December, 1919.

25 ALVAH L. POWELL.
